Primary Examiner — Thomas Johannes*Assistant Examiner* — Shawn T Gingrich(74) *Attorney, Agent, or Firm* — Wolf, Greenfield & Sacks, P.C.(57) **CLAIM**

The ornamental design for an electrically conductive contact, as shown and described.

DESCRIPTION

FIG. 1 is a top, left, front perspective view of an electrically conductive contact according to my design;
 FIG. 2 is a bottom, right, front perspective view thereof;
 FIG. 3 is a bottom, left, front perspective view thereof;
 FIG. 4 is a bottom, left, rear perspective view thereof;
 FIG. 5 is a front elevation view thereof;
 FIG. 6 is a rear elevation view thereof;
 FIG. 7 is a top plan view thereof;
 FIG. 8 is a bottom plan view thereof;
 FIG. 9 is a right side elevation view thereof; and,
 FIG. 10 is a left side elevation view thereof.
